UNITED STATES PATENT OFFICE.

HUGH WILLIAMSON KELLY, OF TRENTON, NEW JERSEY, ASSIGNOR OF ONE-HALF TO
AUBREY LOVE, OF RIDGEWOOD, NEW JERSEY.

TRACK-TORPEDO.

1,248,670.

Specification of Letters Patent.

Patented Dec. 4, 1917.

Application filed May 27, 1916. Serial No. 100,259.

To all whom it may concern:

Be it known that I, HUGH WILLIAMSON KELLY, a citizen of the United States, and a resident of Trenton, Mercer county, New Jersey, have invented certain Improvements in Track-Torpedoes, of which the following is a specification.

My invention relates to track torpedoes of the type set forth generally in my pending applications, Serial Nos. 64,869, 68,545, and 89,075, filed Dec. 3, and Dec. 24, 1915, and Apr. 5, 1916, respectively; the structure constituting my present invention being made in the form of a premolded rubber shell or casing adapted to contain a charge of detonating material; said shell having integral lugs whereby the head of a rail may be gripped in order that the torpedo may be properly positioned with respect to said rail.

In the present structure, the detonating material may be inclosed and confined within a suitable envelop, and the whole may be then introduced into a suitable mold 25 with the desired rubber material and subjected to heat and pressure so as to inclose such charge within a rubber shell having the integral lugs whereby it may be secured to the head of a rail.

30 A further construction consists in forming the shell over a core whereby a chamber is formed to receive the detonating material; a slit being left to permit the introduction of such detonating material, after 35 which such slit is closed.

A modification of these arrangements is a structure in which a rubber lug carrying strap is formed, adapted to be secured to a shell or casing inclosing and carrying a 40 detonating charge.

These and other features of my invention are more fully described hereinafter, reference being had to the accompanying drawings, in which:

45 Figure 1, represents a preformed torpedo of the type constituting my present invention; showing the same in proper position with respect to a rail head.

Fig. 2, is a longitudinal sectional view of 50 the same.

Fig. 3, is an inverted plan view of Fig. 2.

Fig. 4, is a perspective view of such torpedo structure illustrating a modification within the scope of my invention.

55 Fig. 5, is a longitudinal sectional view

illustrating the same modified form of torpedo shown in Fig. 4.

Fig. 6, is a sectional view on the line VI—VI, Fig. 2.

Fig. 7, is a longitudinal sectional view of 60 a torpedo illustrating a further modification within the scope of my invention, and

Fig. 8 is a sectional view on the line VIII—VIII, Fig. 7.

The shell 1, of the torpedo illustrated in 65 Figs. 1, 2, 3 and 6, is a thin-walled structure with the ends beveled as at 2 and the sides as indicated at 3; the base 4 being shaped to conform to the surface of the rail-head, and continuous with the walls of 70 this structure are the rail-engaging lugs 5. In this structure, the charge is disposed within the mold in which the shell is formed; being inclosed in a suitable envelop, capsule, or other container 6, and the 75 rubber and other material to form the shell of the structure is placed within such mold, and the whole subjected to the necessary heat and pressure whereby a continuous shell with rail-engaging lugs is formed, as 80 illustrated in the drawings.

In the form of structure shown in Figs. 4 and 5, the shell is so molded as to leave an aperture or opening 7 whereby the charge may be inserted in the cavity or 85 chamber formed within the shell, after which such opening may be sealed in any suitable manner. In this arrangement, the detonating material may be put in the shell in the form of a preformed charge, or it 90 may be loose material wrapped in an envelop of suitable size and shape to fill the cavity, such as indicated in Fig. 2, or such detonating material may be introduced in loose condition to substantially fill such cavity. In any instance, the charge should be 95 of such a character as not to disarrange or displace the lower wall of the shell which is adapted to rest upon the rail head and is, to a certain extent, arched, as indicated. 100

The structure shown in Figs. 7 and 8, is initially made in two pieces; the lug-carrying strip 5^a and the charge-carrying casing 1^a; the two parts being subsequently secured together by any suitable securing or 105 cementing means, and when finished constituting a torpedo of substantially the same type as those illustrated in the other views.

It will be understood that all of the torpedoes are of substantially the same shape 110

and character as illustrated in the perspective view; they are provided with an arched base portion substantially conforming to the surface of the rail, and they are provided 5 with integral rail-engaging lugs which may have their inner faces roughened by corrugations 10 or other means to assist in retaining the same upon the head of a rail.

In speaking of the shell as made of rubber, 10 it will be understood, of course, that what is meant is a rubber-containing material, the portion of rubber in which may be relatively small. The object is to provide a relatively flexible structure suitable for the purpose 15 and one that will be nonflying under the detonation of the charge. The connection between the lugs and the shell should be of a relatively better grade of material than the shell so as to insure the desired resiliency 20 and at the same time the required tension upon the lugs when they are placed in the rail-engaging position.

I claim:

1. A track torpedo comprising a pre- 25 molded shell of rubber-containing material, and a body of detonating material disposed within said shell, the latter having rail-engaging lugs integral therewith.

2. A track torpedo comprising a pre- 30 molded and arched shell of rubber-containing material, a body of detonating material disposed within said shell and wholly inclosed by the same, and rail-engaging lugs integral with said shell and projecting be- 35 yond the same.

3. The combination of a hollow shell of rubber-containing material having a convex surface substantially arched in two direc-

tions, a body of detonating material within the same, and rail-engaging lugs continuous 40 with the shell and normally disposed toward each other.

4. The combination of a hollow shell of rubber-containing material having a convex surface substantially arched in two directions, a body of detonating material within the same, rail-engaging lugs continuous with the shell, and corrugations formed in said lugs to assist in retaining the torpedo in place. 45

5. A track torpedo comprising a pre-molded shell of rubber-containing material having a cavity and an opening communicating with said cavity, said cavity adapted to receive detonating material, and rail-engaging lugs carried by said shell. 50

6. A track torpedo comprising a pre-molded shell of rubber-containing material having a cavity and an opening communicating with said cavity, said cavity adapted 60 to receive detonating material, after which the opening is sealed, and rail-engaging lugs connected to said shell, said lugs being so connected to the shell as to normally underlie the same and project toward each other. 65

7. A track torpedo comprising a molded shell of rubber or rubber-containing material, and a body of detonating material disposed within said shell.

8. A track torpedo comprising a molded shell of rubber or rubber-containing material, a body of detonating material inclosed by said shell, and a cover for the detonating material interposed between the same and the shell. 70

HUGH WILLIAMSON KELLY.
